UNITED STATES PATENT OFFICE.

JOSEPH A. FISCHER, OF BROOKLYN, NEW YORK, ASSIGNOR TO EUREKA BEDDING MANUFACTURING COMPANY, OF BROOKLYN, NEW YORK, A CORPORATION OF NEW YORK.

DAY-BED WITH ADJUSTABLE FOLDING HEADPIECE.

1,394,985.

Specification of Letters Patent.

Patented Oct. 25, 1921.

Application filed December 22, 1920. Serial No. 432,496.

To all whom it may concern:

Be it known that I, JOSEPH A. FISCHER, a citizen of the United States, residing in Brooklyn, in the county of Kings and State 5 of New York, have invented certain new and useful Improvements in Day-Beds with Adjustable Folding Headpieces, of which the following is a specification.

This invention relates to improvements 10 in day beds, couches and the like, in which there is provided an elevated reclining back piece.

One object of the invention is to provide 15 a back piece as above described, which is pivoted to the frame of the bed, whereby the said back piece may be oscillated to and fro, or folded over upon the face of the bed, as when desired for shipping.

Another object of the invention is to provide 20 suitable means for holding the back piece in adjusted position.

Another object is to provide means of the kind just mentioned comprising an arcuate 25 latch member swingably mounted on the back piece and adapted to engage a stop bar attached to one of the legs, which co-operates with the notches in the arcuate member whereby to hold the back member in any desired elevated position.

30 Another object of the invention is to provide means whereby, when it is desired to throw back the head piece, a foot pedal or other convenient means may be actuated. The foot pedal may be pivoted on the legs 35 on the bed and retained in normal inoperative position by means of a spring, so that when this lever is stepped upon, or operated by hand, it pushes the arcuate latch off the bar and permits the back member to fall 40 downwardly an increment, at which point the lever catches in a notch. Release of the lever throws the latch into contact with the stop bar and the latch moves a little further permitting the next notch to engage the bar.

45 Other objects of the invention will appear as the description proceeds; and while herein minute details of the invention are described, the invention is not limited to these, since many and various changes may be 50 made without departing from the scope of the invention as claimed.

In the accompanying drawing showing by way of example, one of many possible embodiments of the invention,

Figure 1, is a perspective of a bed or couch 55 embodying my invention;

Fig. 2 to 4 are fragmental side elevations showing various steps in the operation of the device; and

Fig. 5 is a fragmental side elevation showing the back piece folded over on the bed for shipping or storing.

The day bed 5, couch or the like is provided with an elevated reclining back piece 6, which is pivoted to brackets 7 secured 65 to the frame 8 of the bed, whereby the said back piece may be oscillated to and fro or even folded over upon the face of the bed 5 (Fig. 5) when desired, as for shipping or storing.

Pivottally attached to the back member 6 near its lower part are a pair of arcuate latch members 10 having a series of notches 11, 12, 13 and 14. Fixed to the legs 17 of the couch is a stop bar 18 which engages in 75 the notches in the arcuate member 10 to hold the back piece in any desired elevated position. When it is desired to move the back piece 6 rearwardly, the U-shaped lever 19 is actuated.

The U-shaped lever 19 has side members comprising foot pedals 20 pivoted on the legs 17 and is retained in normal inoperative position against the flange 21 of the bar 18 by means of a spring 22 strained between 85 the yoke member 25 of the U-shaped lever and a cross bar 26 of the bed frame. When the pedal 20 is stepped upon, it pushes a notch of the arcuate member off the stop bar 18, and the back piece 6 falls downwardly 90 about the distance of half the space between the notches until one of the teeth comes into contact with the yoke member 25; and upon release of the foot pedal, the next tooth moves a little further and engages the stop 95 bar 18. This is repeated as many times as is necessary to bring the back member to the desired position.

The operation of the device is very simple. When it is desired to raise the back piece, as 100 from a position more reclining than that of Fig. 1, the operator merely raises the back piece to the desired inclination and permits the nearest of the notches 11, 12, 13 and 14 to catch on the stop 18.

When it is desired to move the back piece downwardly, the foot pedal 20 is stepped upon, and when this lever is thus actuated,

the yoke 20 engages in, for instance, the lower part of the notch 13 (see dotted lines of Fig. 2) and pushes the notch 12 off the stop bar and permits the back piece to fall downwardly a slight distance until the upper shoulder of the notch 13 comes into contact with the yoke 25 (Fig. 3), thus holding the back piece against further movement. Upon release of the foot pedal, the yoke 25, drawn down by the spring 22, releases the notch 13, and the notch 13 moves a little further until it engages the stop bar 18. As stated, this is repeated as many times as is necessary to bring the back member to the desired position.

A stop pin 27 on the free end of the latch 10 may engage under the retaining pin 28 and against the side edges of the recesses 29 in the stop bar 18, to prevent the accidental raising of the back piece 6 so high that it lets the arcuate latch 10 leave the stop bar 18 and yoke 25 and thus fall out of the cooperative relation with said bar and yoke. When the back piece is to be folded for shipping or storing, as in Fig. 5, the latch 10 must be lifted, as by hand, and to permit the stop pin 27 to pass over the retaining pin 28, as in Fig. 4.

Having thus described my invention, I claim:

1. In combination, a bed frame comprising legs; a head piece pivotally movable on the frame; means pivotally attached to the head piece and movable by increments for changing the inclination of the head piece; a stop member attached to the legs at one end of the frame transversely of the frame and engageable with said means for retaining the head piece at a desired incline; and means pivotally attached to said legs adjacent to the stop member having ends for receiving pressure thereon; the last mentioned means being normally inoperative and being movable by pressure on the ends thereof for engagement with the first mentioned means for releasing the same from engagement with the stop member to permit said means to move for an increment, and upon relief of pressure on said ends permitting further movement of the first mentioned means for engagement thereof with the stop member for changing the inclination of the head piece.

2. In combination, a bed frame comprising legs; a head piece pivotally movable on the frame; latches pivotally attached to the head piece provided with a series of notches; a stop member attached to the legs at one end of the frame transversely thereof and engageable with said notches of the latches for retaining the head piece at a desired incline; and means pivotally attached to said legs adjacent to the stop member having ends for receiving pressure thereon; said means being normally inoper-

ative and being movable by pressure on the ends thereof for releasing the notches of the latches from engagement with the stop member, and permitting movement of the latches for engagement with said means of notches next adjacent in series to the released notches, and upon relief of said pressure permitting further movement of the latches for engagement of said adjacent notches with the stop member.

3. In combination, a bed frame comprising legs; a head piece pivotally movable on the frame; latches pivotally attached to the head piece provided with a series of notches; a stop member attached to the legs at one end of the frame transversely thereof and engageable with said notches of the latches for retaining the head piece at a desired incline; and means pivotally attached to said legs having ends for receiving pressure thereon; the stop member being rectangular in cross-section and said means being normally inoperatively retained in the angular cross-sectional portion of the stop member, and being movable by pressure on said ends for releasing the notches of the latches from engagement with the stop member, and permitting movement of the latches for engagement with said means of notches next adjacent in series to the released notches, and upon relief of said pressure permitting further movement of the latches for engagement of said adjacent notches with the stop member.

4. In combination, a day bed, couch or the like having a frame and legs; a bracket secured to the frame and legs near the head end of the bed; an elevated reclining back piece pivoted to the brackets, whereby the said back piece may be oscillated to and from, or folded over upon the face of the bed; arcuate latches swingably attached to the lower part of the back member, each provided with a series of notches; a stop bar attached to said legs and adapted to receive the notches of the latches, whereby to hold the back piece in any desired elevated position; a U-shaped lever comprising a yoke member, and side arms forming foot pedals pivoted on the legs; a spring strained between said U-shaped lever and the frame for retaining the lever in normal inoperative position; said yoke member acting when the pedal is stepped upon to push the latches off the latch bar to permit the back member to fall downwardly an increment throwing a tooth into contact with the yoke, and upon release of the foot pedal permitting the next tooth to move a little further and engage the stop bar.

5. In combination, a day bed, couch or the like having a frame and legs; brackets secured to the frame and legs near the head of the bed; a back piece pivoted to the bracket whereby the back piece may be os-

cillated to and fro or folded over upon the face of the bed; arcuate latches swingably attached to the lower part of the back piece each provided with a series of notches; a 5 stop bar attached to said legs and adapted to receive the notches of the latches, whereby to hold the back piece in desired elevated position; a U-shaped lever comprising a yoke member, and side arms forming pedals 10 pivoted on the legs; a spring strained between said U-shaped lever and the frame for retaining the lever in normal inoperative position; said yoke member acting when pressure is exerted upon the pedal to push 15 the latches off the stop bar to permit the back member to fall downwardly an increment thereby throwing another notch of the series into contact with the yoke, and upon relief of pressure on the pedal permitting 20 the latches to move a little further and to engage said notch with the stop bar.

6. In combination, a bed frame; an elevated reclining back piece pivoted to the frame, whereby the said back piece may be 25 oscillated or folded over upon the frame; latches pivotally attached to the lower part of the back piece, and each provided with notches; a stop bar attached to and adapted to be engaged by the notches, whereby to hold 30 the back piece in any desired position; retaining pins in said stop bar; and stop pins

in the free ends of the latches and engageable under the retaining pins to prevent the latches from leaving the stop bar.

7. In combination, a bed frame; an ele- 35 vated reclining back piece pivoted to the frame, whereby the said back piece may be oscillated to and fro or folded over upon the face of the bed; arcuate latches swingably attached to the lower part of the back 40 piece, each provided with a series of notches; a stop bar attached to said frame and provided with recesses adapted to receive the arcuate latches, and to be engaged by the notches, whereby to hold the back piece in 45 any desired position; retaining pins in said stop bar near said recesses; and stop pins in the free ends of the latches and engageable under the retaining pins and against the side edges of said recesses to prevent the 50 accidental raising of the back piece so high that it lets the arcuate latch leave the stop bar; the latches being adapted to be lifted, as by hand, and to permit the stop pins to pass over the retaining pins, when the back 55 piece is to be folded over the frame as for shipping or storing.

JOSEPH A. FISCHER.
